UNITED STATES PATENT OFFICE.

FRANK E. JONES, OF PAWTUCKET, RHODE ISLAND, ASSIGNOR TO HEMPHILL MANUFACTURING COMPANY, OF PAWTUCKET, RHODE ISLAND.

YARN-FINGER MECHANISM FOR KNITTING-MACHINES.

1,136,343.

Specification of Letters Patent. Patented Apr. 20, 1915.

Application filed June 4, 1914. Serial No. 843,951.

To all whom it may concern:

Be it known that I, FRANK E. JONES, citizen of the United States, residing at Pawtucket, Rhode Island, have invented certain new and useful Improvements in Yarn-Finger Mechanism for Knitting-Machines, of which the following is a specification.

My invention relates to yarn finger mechanism, and is shown in connection with a knitting machine of the general type known as the "Banner," though it will be understood that the invention is not confined to its use or combination with a machine of this particular make.

The invention concerns particularly a spring arrangement for pressing the yarn fingers downwardly to their operative position, one object of the invention being to provide a unit which will serve a number of yarn fingers and may be applied to or removed from the machine as one body or unit so that by simply attaching this unit in place each yarn finger will have the necessary spring tension applied thereto for moving it to operative position when the controlling or operating lever permits the spring to act.

Another object of the invention is to provide individual springs for the yarn fingers which will be certain in action and durable in use.

Other objects of the invention will appear from the following description.

In the accompanying drawings Figure 1 is a side view of so much of a knitting head with the invention applied thereto as is necessary to a clear understanding of the construction and relation of my invention to the yarn fingers and knitting head; Fig. 2 shows the spring unit detached from the machine; Fig. 3 is a front view of Fig. 2 looking from the left of said figure; Fig. 4 is a plan view of the spring unit with the cover plate removed; Fig. 5 is a side view of one of the plungers with its spring; Fig. 6 is a front view of the upper part of the post or standard in which the yarn finger operating levers are mounted; Fig. 7 is a detail view of the link connection between the operating levers of the yarn fingers and the pattern drum.

In machines of the general type known as the "Banner," a group of yarn fingers is employed pivotally mounted at the same

point in relation to the knitting head, and 55 in the particular construction shown wherein a latch ring 1 is employed the yarn fingers of the group are pivoted on a pin 2 held in ears, one of which is shown at 3, extending up from the latch ring. 60

In Fig. 1 one of the yarn fingers, as indicated at 4, is shown in its elevated or inoperative position, and at 4' one of the arm fingers is shown in dotted lines in its lowered or operative position, that is, in position to feed the yarn to the needles. Each yarn finger has a tail portion 5, and heretofore it has been customary to provide a leaf spring for each yarn finger, these springs being attached to the rear portion of the 70 latch ring, and extending upwardly to bear on the tail portions 5 to press the yarn fingers downwardly. These leaf springs, however, being subjected to much vibration due to the raising and lowering of the yarn fingers, have been found objectionable because of breakage and loss of power. Directly connected spiral springs of the pull variety have also been employed, but these have been found inefficient, and my object is to 75 provide an arrangement which will be efficient in use, readily applied and removed as one body, and by which, when in proper position, each yarn finger will have its individual spring combined therewith. 80

In carrying out my invention, I provide a casing 6 having a downwardly extending portion 7 attached by screws 8 to the side of the latch ring, the main portion of this casing inclining downwardly and laterally, 90 and serving as a housing for the spring members which individually press upon the tail portions of the yarn fingers. These spring members consist of plungers 9, one for each yarn finger, said plungers consisting of flat bars set up on edge and moving in straight slots or ways 10 formed in the block or frame 6 parallel with each other and from end to end. The plungers have portions at 10' reaching from the bottoms of 100 these ways or slots to the upper surface of the block, and by securing the cover plate 11 in place the several plungers are confined and accurately guided in their movement.

The forward ends of the plungers are 105 rounded, and bear upon the tail portions 5 of the yarn fingers, and they are pressed into this position by springs 12, one for each

plunger, said springs being located in pockets 13 extending along the guideways 10 from the front end of the casing to the point 14, where a shoulder is formed to provide a seat for the spiral springs. The plungers 9 are recessed or cut away, as shown at 15, between the upstanding parts 10', and the springs lie in these recesses or cutaway portions of the plungers. They bear upon the forward upstanding portion 10', and thus serve to press the plungers forwardly. In other words, the springs bear upon the shoulders 14 in the frame or block 6 at one end, and upon the forward upstanding portion 10' of the plungers at their other ends, it being understood that the bores or pockets 13 extend clear to the front face of the block or frame 6. The springs are maintained in connection with the plungers, should any of these be removed, by a rod or pin 16 held by the rear portion of the plunger and extending longitudinally within the spiral spring. The front ends of the plungers are suitably bent, as shown in Fig. 4, to bear upon the particular yarn finger to which they belong. The yarn fingers are raised to inoperative position by a group of levers one of which, being shown in its lowered position at 17 in full lines, allows its yarn finger to assume the position shown at 4', and at 17' one of the operating levers is shown in its elevated position to raise its yarn finger up, as shown at 4. When any yarn finger is raised its tail portion 5 having a camming action against the rounded end of the plunger, will force this plunger rearwardly against the action of the spring which is under compression, and this plunger will therefore slide in its guideway of the block 6 for this compressing action. When the operating lever is lowered, the compression spring will relax, and force its plunger forwardly, and this, acting against the tail piece of the yarn finger, will move the same down to operative position. Any or all of the plungers may be removed without taking the block from the machine by removing the cover 11. By removing the block from the machine the whole spring mechanism is moved as one unit, together with the plungers, and then any one or all of the plungers may be removed from the block, together with the springs, by simply sliding the plunger or plungers forwardly. Notwithstanding the fact that the plunger guide grooves extend through from end to end of the block, these plungers will be prevented from being removed from the block toward the rear or falling out by the springs bearing on the shoulders at 14 at one end, and upon the plungers at their other ends. The yarn finger lifting levers 17 are pivotally mounted at 18, and for guiding them I provide a comb plate at 19 held in the recess at the upper end of the standard 20, being

held in this position by the screw 21. The lifting levers are operated by link 6, one of which is shown at 22, pivoted on a flanged button 23 held by a screw 24 passing through the button and into the lever. This link is made in two parts, the part 22' having a threaded socket to receive the threaded end of the part 22, and by removing the screw 24 and thus detaching the link from its lever 17 the length of the link may be adjusted by simply giving the portion 22 one or more turns and attaching it again to the lever 17. The link at its lower end is connected at 25 to a lever 26 operated by a pattern drum. It will be seen that the spring device is self-contained, consisting of one unit, and including individually movable plungers controlled by compression springs for applying the necessary pressure to the yarn fingers. 85

Fig. 2 illustrates the unitary character of my device, this being detached from the machine and carrying all of the plungers with their springs. 90

I claim as my invention:

1. In combination a series of pivoted yarn fingers having tail portions on the opposite side of the pivots from their main portion, lifting means therefor, a series of plungers bearing upon the tail portions of the yarn fingers, and springs for operating the plungers, said lifting means being independent of the plungers and compression springs, substantially as described. 95
2. In combination a series of pivoted yarn fingers having tail portions, lifting means therefor, a series of plungers bearing upon the tail portions of the yarn fingers, springs for operating the plungers, and supporting means carrying the plungers and springs 105 and constituting therewith a unit detachably secured to the machine, substantially as described.
3. In combination a series of pivoted yarn fingers having upwardly extending tail portions on the opposite side of their pivots from their main portions, lifting means, a series of plungers slidably mounted in inclined position and bearing on the said tail portions, and springs acting on the plungers, 110 said lifting means acting on the main portions of the yarn fingers and independent of the plungers and compression springs, substantially as described. 115
4. In combination a series of pivoted yarn fingers, lifting means therefor, a series of plungers, a box carrying said plungers and having guideways therefor, and pockets for springs, springs in said pockets, said plungers having recesses in which the springs 120 are located with one end bearing on the bottom of the pocket and the other end bearing on the plunger, said plunger projecting into engagement with the tail portions of the yarn fingers, substantially as described. 125

5. In combination yarn fingers having tail portions and pivotally mounted, a series of 10
slidable plungers, a box arranged in inclined position and having guides for the plungers, springs pocketed in the box and engaging the plungers to force them against the tail pieces of the yarn fingers, said box, together with the plungers and springs, con-

stituting one unit detachably mounted on the machine, substantially as described.

In testimony whereof, I affix my signature in presence of two witnesses.

FRANK E. JONES.
